LOOPER MECHANISM FOR SEWING-MACHINES.

1,230,355.

Specification of Letters Patent. Patented June 19, 1917.

Application filed August 28, 1915. Serial No. 47,743.

To all whom it may concern:

Be it known that we, JOHN P. WEIS and ALBERT H. WEIS, citizens of the United States, residing at Nyack, in the county of Rockland and State of New York, have invented certain new and useful Improvements in Looper Mechanism for Sewing-Machines, of which the following is a specification.

10 This invention relates to sewing machines, and more particularly to the stitch-forming mechanism thereof for making parallel rows of chain stitching, wherein the needles and loopers may be placed close to one another.

15 to provide a wide range of needle gages for various classes of work where multiple stitching is required. The present improvement, however, more particularly resides in an improved looper mechanism whereby the

20 loopers may have a very short stroke, for instance about a half-inch movement into and out of the needle loop, and a very narrow lateral vibration or movement from one side to the other of the needles.

25 Heretofore in machines of this character the looper movement is usually the same as the movement of the needle; that is to say, where the needles moved an inch and a quarter the loopers moved a corresponding

30 distance so as to travel at the same speed. In other machines, where the looper movement is less than that of the needles, a dwell is given to the loopers at the front and rear of such movement to compensate for the

35 greater movement of the needles, so that the needle when presenting its loop to the looper would be traveling at substantially the same speed as the looper. Consequently a jerky, irregular and unsteady movement is the result, and wear, lost motion and objectionable noise result. This is entirely overcome in the present improvement, by reason of the short steady movement given to the loopers and the needles. The loopers being

40 very short and thin at the loop engaging portion thereof enables them to pass into and out of very small needle loops and so greatly assist in the handling of threads and the forming of the stitches with a minimum

45 of tension on the threads.

50 Another advantage is that with this short movement of the loopers no thread take-up, nipper or measuring devices are necessary, the thread is not serfed through the eyes of

the looper, and practically no tension is required on the looper threads and consequently a very tight and flat stitch can be drawn well into the work with very little tension on the needle threads.

The short movement of the loopers also permits the use of a very rigid feeding mechanism, as the shank of the feed may be close to the needles and operate directly under the main pressure of the presser foot, whereas in the machines where a long looper throw is used a great overhang of the feed dogs is necessary, which greatly interferes with the proper feeding of the work.

In the drawings accompanying and forming a part of this specification, Figure 1 is a front view illustrating the looper mechanism, the cloth and throat plates being partly in section to clearly illustrate the juxtaposition of the parts; Fig. 2 is a top plan view illustrating the loopers with the top arm of the machine and the cloth plate removed to clearly show the parts underneath the same; Fig. 3 is a sectional view taken on line 3—3, Fig. 2, and looking in the direction of the arrow, Fig. 2; Fig. 4 is a detail view of the looper oscillating eccentric crank connection, partly in section, and taken in line 4—4, Fig. 2; Fig. 5 is a detail view illustrating the right angle gear drive of the crank shaft for vibrating the loopers laterally; Fig. 6 is a diagrammatic view illustrating the path of travel of each looper; Fig. 7 is a perspective view illustrating the relative positions of the cloth plate and throat plates; Fig. 8 is a detail perspective view illustrating the throat plate with its top plate removed; and Fig. 9 is a bottom view of the throat plate illustrating the peculiar construction of the needle holes and the thread engaging and looper thread strand retaining slots.

Similar characters of reference indicate corresponding parts in the different figures of the drawings.

The base plate or bed 1 of the machine carries the upright portion 2 of the overhanging arm 3, which carries the usual needle presser bar mechanism generally indicated by 4. The needle holder 5 is carried by the needle bar for operating the usual needles 6, shown in the present instance as two in number. The needle operating lever 7 is actuated by the usual pit-

man connection 8 and wheel eccentric 9 carried by the main driving shaft 10. The cloth plate 11 is secured at one end to the upright part 2 of the overhanging arm 3, the other end being secured at 12 to the front bearing 13 in which the main shaft 10 operates. A web or guard 14 is carried by the front end of the cloth plate 11 to guard certain of the moving parts. The usual 10 feeding mechanism may be employed, and this comprises an adjustable crank 15 carried on the main driving shaft 10 and a pitman connection 16 to operate a rocker frame 17 connected with the feed bar 18 to operate 15 the feed dogs 19, see Figs. 2 and 3. A feed lift eccentric 20 gives the necessary rise and fall to the feed dogs, while the adjustable crank 15 gives the to-and-fro movement to such feed dogs. A looper bracket 21 is secured to the bed of the machine and has an 20 end bearing 22 for the looper shaft 23 and a similar bearing 24, see Fig. 1, located intermediate its length. This bracket 21 also has two bearings 25 and 26, see Fig. 2, 25 wherein the looper vibrating crank shaft 27 is supported. A bevel gear 28 is secured to this crank shaft 27 and meshes with a similar bevel gear 29 carried on the main driving shaft 10 to transmit rotary motion to the crank shaft 27. This crank shaft 27 is 30 provided with a crank 30 operating between the bearings 25 and 26 and has thereon a split block 31 which operates in a fork 32 carried by looper shaft 23, it being adjustably secured thereon by a screw 33, and this 35 mechanism imparts lateral movement to the loopers in the path illustrated in Fig. 6. Secured to the main driving shaft 10 is an eccentric 34 rotating in a strap connection 40 having its other end pivotally secured to a crank 37, and this crank is secured to the looper shaft 23 for rocking the loopers into and out of the needle loops. The face or width of the eccentric 34 is slightly wider 45 than the strap connection 35 so that as the strap connection is operated laterally by the crank 30 the strap connection will always have a full bearing on the eccentric. Looper carriers 38 are secured to the looper shaft 23 and carry loopers 39 having loop-engaging 50 blades 40 with the usual thread eyes and grooves on one side thereof. The usual presser foot 41 is employed to coöperate with the feed 19 to carry the work past the 55 stitching position.

In the operation of the machine the bevel gears 28 and 29 are so timed with relation to the eccentric 34 as to cause the loopers to move forward toward the needles at an 60 angle thereto, so that there is no possibility of the loops of needle thread twisting away from the looper as it advances forward. This movement has the added advantage of placing the strands of thread into a slot 65 hereinafter described in the bottom of the

throat plate wherein the thread is held at one side of the needle holes while the needle is coming down to enter between the thread and the looper in the forming of the double thread chain stitch. In Fig. 3 the looper 70 will be seen in its foremost position at the time the needle reaches its full height, and as the needle comes down the looper is moved backward and laterally and the strand of thread indicated by 43 is drawn 75 into the groove or slot 42 and held or retained to one side. On certain classes of work it is desirable to use a right-hand looper, while in other cases a left-hand looper is more advantageously used. The 80 change from one to the other merely necessitates a change of the loopers and a reversing of the timing of the crank 30 by shifting the gears 28 and 29 to change the path 85 of travel of the loopers as represented by Fig. 6, so that the loopers will come in and go out on the opposite sides of the needles, in which case the needles are also threaded from the opposite side.

The improved throat plate, and its cloth-supporting plate, is described and claimed in the contemporaneously pending application of Albert H. Weis, Serial No. 41,024, filed July 21, 1915, and assigned to the same company to which this case is assigned, and therefore only a brief description is deemed necessary herein. The cloth plate 11, see Figs. 7 to 9, is milled or recessed to receive the bottom throat plate 50, which is secured to the cloth plate by the usual screws 51. We prefer to use screws and screw holes for attaching the plate which will provide a slight adjustment at right angles and parallel with the milled or recessed surface of the cloth plate 11 to facilitate in lining up 90 the needle holes in the throat plate with the needles. To accomplish this the holes in the plate may be enlarged as shown at 52 and the recess in the cloth plate 11 be slightly larger than the throat plate 50 to permit its 100 adjustment. The bottom plate 50 is provided with the usual feed slots 53, which may be of any form to suit the character of feed used, and the character of feed is usually designed to suit the number of needles 110 and the style of work for which the machine is to be used. For lap seam felling work it is desirable to have the feed slots extend up to and slightly in front of the needles, as at 115 54. The needle holes 55 for the needles are 120 on the bottom of the plate enlarged slightly, as at 56, to give clearance for the looper threads and a saw cut or groove 42 extends from each needle hole, this groove being located at one side thereof and enables a 125 strand of the looper thread 43 to be placed therein as the looper moves forward in the formation of the stitch. Each groove has at one side a substantially straight wall 12' and at its opposite side a wall terminating 130

adjacent to the needle opening in a projection 12" shown herein as V-shaped, which extends in the plane of the plate and does not project below the bottom surface of the 5 plate. Heretofore pins, spreader bars, etc., have been used for the purpose of spreading and thereby forming a loop, but we have found in practice that the pins or spreader bars become disarranged and the threads are 10 apt to hook over the same so as to snag and break the thread. Moreover, the pins become worn, as there is but a very small portion of them which coats with the threads, and when they are worn they do not perform 15 their functions properly. This has been overcome by the present improvement, as the grooves are of considerable length, so that the thread is retained during the entire forward movement of the looper and 20 there is no possibility of the thread snagging, as there is no portion upon which the thread could catch or hook and there are no projections below the bottom of the throat plate for the looper to interfere with, and 25 consequently the thread is more accurately handled thereby. In the present improvement as above stated, the strand or thread of the looper is held or retained during a certain part of the movement of the looper 30 and this results in holding or retaining one strand of the looper thread to one side of the needle hole while the needle is descending to enter between it and the looper body. In other words, the present strand retaining 35 device does not act in any similar way to pins or projections extending below the throat plate, which necessarily spread the thread and form a loop and so require a take-up device of some kind to take up this 40 extra thread loop where it is cast from the pins. In the present improvement, as hereinbefore stated, at the top of page 3, no take-up device is necessary or required to take up the looper thread for the reason that there 45 is no loop formed by this retaining device. As the looper moves backward and laterally the thread is drawn from the retaining device in proportion to the movement of the looper, so that therefore there is no excess 50 amount of thread or a loop to be taken up.

In the operation of the needles and the loopers, the looper thread of each looper is carried forward as the looper enters the needle loop. The loopers move sidewise and 55 as these movements take place the strand of each looper thread extending from the forward eye of the looper to the previous stitch passes into the groove or saw cut 42 so as to be held or retain to one side of the 60 needle hole as the needle is descending to take a loop of thread from the looper.

Threaded holes 57 are provided in the bottom or main plate 50 for attaching the top plate 58, which has similar holes 59 to receive 65 screws. This removable and renewable

top plate 58 has feed slots 60 corresponding with the feed slots 53 and 54 of the bottom plate and is also provided with needle slots or holes 61 corresponding with the needle holes 55 of the bottom plate. It is obvious 70 that the front edge of these top plates may be grooved, slotted or otherwise shaped so as to guide the work or seams as the case may be. The throat plate 50 has an extending portion 62 in front of the needles and is cut away, as at 63, at each side thereof and has extending ends 64. The removable slide plate 65, see Fig. 8, fits into the irregular shaped opening formed in the front of the plate 50 indicated by the parts 64, 63 and 62. 75 The slide plate rests on the rabbeted part 63 of the cloth plate 11 and is provided with a plate spring, (not shown), on the underside thereof to rest against the bottom of the cloth plate and hold the slide plate 65 in 80 position. This slide plate 65 may carry a folder or other attachment. These are sometimes secured to the bottom for running a strip underneath the garment. The removal of this slide plate affords quick and 85 easy access to the mechanism below the cloth plate. 90

In the present improvement the looper shaft 23 is shown located close to the bed plate 1 of the machine and about one-quarter 95 of an inch forward of the needle, that is to say, the axis of the looper shaft 23 is about one-quarter of an inch forward of the working path of the needle, (see dotted lines *a* and *b*, Fig. 3). The distance from the looper shaft to the bottom of the throat plate is shown approximately two and one-half inches, so that the looper swings on that radius with the result that the looper on its forward movement operates very close to the bottom of the throat plate in front of the needle hole, so that it is not necessary to have any projecting fingers or pins below the bottom surface of the throat plate to form 100 a loop in the looper thread. In other words, this location of the looper in the manner described is such that the looper will coöperate with the groove or slot formed retaining device in the throat plate, even though it does not extend below the bottom surface on such throat plate. This permits the needle loop to cast off from the looper blade on the backward movement thereof as the looper is moving sidewise during such backward movement. This action of the looper upon 105 the looper thread or strand is due to the movement of the looper sidewise or laterally away from the retaining groove and the looper does not during its forward movement cast a loop around any projecting pin 110 or loop spreader which, when used, has been located forwardly of the needle hole to form a distinct loop requiring a take-up device to take up the loose thread of this loop. In short, in the present improvement there is 115 120 125 130

no pin or projection below the throat plate which draws off the looper thread to form a loop. The point of the looper tips up slightly to release the needle loop and permits the drawing up of a tighter stitch and also enables a stronger feed to be used.

The various details may be more or less changed without departing from the spirit or scope of the present improvement.

10 We claim as our invention:

1. The combination of feeding mechanism, a needle, a throat plate having a groove and thread retaining means carried by a wall of said groove for retaining the looper thread so as to permit the needle to pass between the looper thread and the body of the looper, a looper constructed and positioned to coöperate with said retaining means, means for moving said looper into the needle loop in a line substantially parallel with the line of feed and for withdrawing the looper from the needle loop, and means for giving the said looper a lateral movement.

2. The combination of feeding mechanism, a plurality of needles arranged in a line substantially at right angles to the line of feed, a throat plate having grooves and thread retaining means carried by the walls of said grooves for retaining the looper threads of the loopers to permit each needle to pass between the looper thread and the body of the looper with which it coöperates, a thread carrying looper coöperating with each needle and constructed and positioned to coöperate with its retaining means, means for moving said loopers into and out of their respective needle loops, each looper moving into the needle loop in a direction opposed to the direction of feed and in line substantially parallel with the line of feed, and means for moving the loopers laterally.

3. The combination of feeding mechanism, a needle, a looper, means for moving said looper back and forth in a plane substantially parallel with the line of feed, means for giving said looper a lateral movement during its back and forth movement, a throat plate and looper thread retaining means carried thereby above the bottom surface thereof and arranged in the path of the looper thread whereby the looper thread engaged by the retaining means is held in position to permit the entrance of the needle between said looper body and the looper thread, said looper constructed and positioned to coöperate with said retaining means.

4. The combination of a needle, a looper, means for moving said looper in one direction in substantially a right line on one side 60 of the needle path and substantially parallel with the line of feed and for moving said looper in substantially a right line on the other side of the needle path in the opposite direction and for giving said looper a lateral movement during its back and forth move-

ment, a throat plate, a looper thread retaining means carried thereby above the bottom surface thereof and arranged in front of the needle relative to the movement of the looper and in the path of the looper thread whereby said looper thread is retained in position to permit the entrance of the needle between said looper and said looper thread.

5. The combination with a plurality of needles and loopers and means for operating the same, of a throat plate having a plurality of needle slots and adjacent thereto and above the bottom surface thereof loop retaining means, one for each looper for engaging the threads carried by the loopers and positioning the same for the entrance of the needles between said threads and the bodies of the loopers, said loopers constructed and positioned to coöperate with said thread retaining means.

6. The combination of feeding mechanism, a needle, a throat plate having a slot and looper thread retaining means above the bottom surface of the plate and arranged in the path of the looper thread whereby the looper thread in said slot is retained in position to permit the entrance of the needle between said looper body and the looper thread, a looper constructed and positioned to coöperate with said retaining means, and means for moving the looper back and forth and for giving it a lateral movement during such back and forth movement.

7. The combination of a throat plate, feeding mechanism, a needle, looper thread retaining means located within the throat plate and arranged in the path of the looper thread whereby the looper thread engaged by said means is retained in position to permit the entrance of the needle between said looper body and the looper thread, a looper constructed and positioned to coöperate with said retaining means, and means for moving the looper back and forth and giving it a lateral movement during such back and forth movement.

8. The combination of a throat plate, feeding mechanism, a needle, looper thread retaining means located entirely above the bottom of said throat plate and arranged in the path of the looper thread whereby the looper thread engaged by said means is retained in position to permit the entrance of the needle between said looper body and the looper thread, a looper constructed and positioned to coöperate with said retaining means, and means for moving the looper back and forth and giving it a lateral movement during such back and forth movement.

9. In a sewing machine having a throat plate provided with needle slots and a plurality of needles and loopers, and means for operating said needles and loopers, the combination of looper thread retaining means located wholly within the throat plate and ex-

5 tending in a plane parallel with the plane of the plate and lying adjacent to the needle slots for engaging the threads carried by the loopers and positioning the same for the entrance of the needles between said threads and the bodies of the loopers, said loopers constructed and positioned to coöperate with said retaining means.

10. In a sewing machine the combination 10 of a throat plate provided with a needle slot, a needle, a looper, means for operating the needle and looper, and looper thread retaining means located above the bottom of the throat plate for engaging the looper thread and positioning the same for the entrance 15 of the needle between said thread and body of the looper, said looper constructed and positioned to coöperate with the looper thread retaining means located above the bottom of the throat plate.

11. In a sewing machine the combination 20 of a throat plate provided with a needle slot, a needle, a looper, means for operating the needle and looper, and looper thread retaining means located wholly within the throat plate and extending in a plane parallel with the plane of the plate and lying adjacent to the needle slot for engaging the looper thread and positioning the same for the entrance 25 of the same between said thread and the body of the looper, said looper constructed and positioned to coöperate with the looper thread retaining means located in the throat plate.

30 12. In a sewing machine the combination 25 of a throat plate having a needle slot, a needle, a looper, means for operating said needle and looper, and looper thread retaining means forming a continuation of the needle slot for engaging the looper thread and positioning the same for the entrance of the needle between said thread and bottom of the looper, said looper constructed and positioned to coöperate with said looper thread retaining means.

40 13. In a sewing machine the combination 35 of one or more needles, a two-part throat plate comprising a bottom plate and a renewable top plate having one or more registering needle openings and one or more looper thread retaining means located in the bottom plate for retaining a thread loop, one or more loopers constructed and positioned to operate with the looper thread retaining 45 means located in the bottom plate, and means for operating the needles and looper.

50 14. In a sewing machine the combination 45 of one or more needles, a two-part throat plate comprising a bottom plate and a renewable top plate having one or more registering needle openings and one or more looper thread retaining means located in the bottom plate for retaining a thread loop, one or more loopers constructed and positioned 60 to operate with the looper thread retaining

means located in the bottom plate, and means for operating the needles and looper, the number of looper thread retaining means corresponding to the number of needles and loopers.

70 15. In a sewing machine the combination 75 of a throat plate provided with one or more needle slots, one or more needles, one or more loopers, each having a movement in an elliptical path, means for operating said needle and looper, and looper thread retaining means in the throat plate adjacent to each needle slot and comprising a slot formed portion for receiving the thread carried by each looper, and positioning the same for the entrance of the needle between said thread and the body of the looper, each of said loopers constructed and positioned to coöperate with said looper thread retaining means located in the throat plate.

80 16. In a sewing machine having a throat plate provided with one or more needle slots, one or more needles, one or more loopers, each having a movement in an uninterrupted elliptical path, means for operating 85 said needle and looper, and looper thread retaining means in the throat plate adjacent to each needle slot and comprising a slot formed portion for receiving the thread carried by each looper and positioning the same for the entrance of the needle between said thread and the body of the looper, each of said loopers constructed and positioned to coöperate with said looper thread retaining means located in the throat plate.

90 17. In a sewing machine having a throat plate, the combination of a needle, looper thread retaining means so formed in the throat plate as not to project below the bottom thereof, a looper constructed and positioned so as to coöperate with the said thread retaining means notwithstanding it does not project below the bottom of the throat plate, and means for operating the needle and the looper.

100 18. In a sewing machine having a throat plate, the combination of a needle, looper thread retaining means so formed in the throat plate as not to project below the bottom thereof and including a groove extending in the plane of the plate, a looper constructed and positioned so as to coöperate with the said thread retaining means notwithstanding it does not project below the bottom of the throat plate, and means for 105 operating the needle and the looper.

110 19. In a sewing machine having a throat plate provided with a needle opening, the combination of a needle, looper thread retaining means so formed in the throat plate 115 as not to project below the bottom thereof and comprising a groove extending in the plane of the plate, one of the walls of said groove terminating adjacent to the needle opening in a projection, a looper constructed 120

125

130

- and positioned so as to coöperate with said thread retainer notwithstanding it does not project below the throat plate, and means for operating the needle and looper.
5. 20. In a sewing machine having a throat plate provided with a needle opening, the combination of a needle, looper thread retaining means so formed in the throat plate as not to project below the bottom thereof and comprising a groove extending in the plane of the plate, one of the walls of said groove terminating adjacent to the needle opening in a substantially V-shaped projection, the axis of the looper being located forward of the path of movement of the needle so that the looper on its forward movement operates close to the bottom of the throat plate in front of the needle hole to coöperate with the looper thread retaining means. 70
10. 21. In a sewing machine having a throat plate provided with a needle opening, the combination of a needle, a looper, means for operating said needle and looper, and looper thread retaining means so formed in the throat plate as not to project below the bottom thereof, the axis of the looper being located forward of the path of movement of the needle so that the looper on its forward movement operates close to the bottom of the throat plate in front of the needle hole to coöperate with the looper thread retaining means. 80
15. 22. In a sewing machine having a throat plate provided with a needle hole, the combination of a needle, a looper, means for operating said needle and looper, and looper thread retaining means so formed in the throat plate as not to project below the bottom thereof and comprising a groove extending in the plane of the plate, the axis of 85
25. 40. the looper being located forward of the path of movement of the needle so that the looper on its forward movement operates close to the bottom of the throat plate in front of the needle hole to coöperate with the looper thread retaining means. 90
30. 45. 23. In a sewing machine having a throat plate provided with a needle hole, the combination of a needle, a looper, means for operating said needle and looper, and looper thread retaining means so formed in the throat plate as not to project below the bottom thereof and comprising a groove extending in the plane of the plate and a projection extending from a wall of said groove, the axis of the looper being located forward of the path of movement of the needle so that the looper on its forward movement operates close to the bottom of the throat plate in front of the needle hole to coöperate with the looper thread retaining means. 95
35. 50. 24. In a sewing machine having a throat plate provided with a needle opening, the combination of a needle, a looper, means for operating the same, and looper thread re- 100
40. 55. 25. In a sewing machine having a throat plate provided with a needle opening, the combination of a needle, a looper, means for operating the same, and looper thread retaining means located in the throat plate to one side of the needle slot and comprising a slot opening into the needle slot, a looper constructed and positioned to coöperate with said thread retaining means, and means for operating the needle and looper. 105
45. 60. 26. In a sewing machine the combination of one or more needles and loopers, means for actuating the same, a throat plate and looper thread retaining means carried by the throat plate above the bottom surface thereof for engaging the thread strand carried by each looper and positioning the same for the entrance of the needle between said thread and body of the looper, said looper having its axis so located that it will during its movement operate close to the bottom of the throat plate to coöperate with said looper thread retaining means above the bottom of such plate. 110
50. 65. 27. In a sewing machine the combination of one or more needles and loopers, means for actuating the same, a throat plate, and looper thread retaining means carried by the throat plate above the bottom surface thereof for engaging the thread strand carried by the looper and positioning the same for the entrance of the needle between said thread and body of the looper, said looper having its axis located forwardly of the path of movement of the needle, whereby during the forward movement of the looper it will operate close to the bottom of the throat plate and coöperate with the looper thread retaining means above the bottom of such plate. 115
55. 70. 28. In a sewing machine having a throat plate provided with one or more needle openings, the combination of one or more needles and loopers, means for operating the needles and loopers, and looper thread retaining means including a slot carried by the throat plate and corresponding in number with the number of coöperating needles and loopers and each lying adjacent to a needle opening for engaging a looper thread and positioning the same for the entrance of a needle between the thread and the body of the looper, each of said loopers 120
60. 75. 65. 29. In a sewing machine having a throat plate provided with a needle opening, the combination of a needle, a looper, means for operating the same, and looper thread retaining means so formed in the throat plate as not to project below the bottom thereof and comprising a groove extending in the plane of the plate, one of the walls of said groove terminating adjacent to the needle opening in a substantially V-shaped projection, the axis of the looper being located forward of the path of movement of the needle so that the looper on its forward movement operates close to the bottom of the throat plate in front of the needle hole to coöperate with the looper thread retaining means. 125
65. 70. 30. 24. In a sewing machine having a throat plate provided with a needle opening, the combination of a needle, a looper, means for operating the same, and looper thread retaining means located in the throat plate to one side of the needle slot and comprising a slot opening into the needle slot, a looper constructed and positioned to coöperate with said thread retaining means, and means for operating the needle and looper. 130

having its axis so located that the looper will operate close to the bottom of the throat plate.

29. In a sewing machine having a throat plate provided with one or more needle holes, the combination of one or more needles, one or more loopers located in position to operate close to the bottom of said throat plate, means for actuating the needle and looper, and looper thread retaining means carried by the throat plate and corresponding in number with the number of co-

operating needles and loopers, each of said looper thread retaining means located in proximity to its needle hole and effective to 15 retain the looper thread to permit the passage of the needle between the thread and the looper but ineffective to form a loop in the looper thread.

Signed at Nyack, in the county of Rock- 20 land and State of New York, this 21st day of August, 1915.
